UNITED STATES PATENT OFFICE.

CHARLES M. WEEKS, OF SPRINGFIELD, MASSACHUSETTS.

PUNCHING-BAG MACHINE.

1,233,005.

Specification of Letters Patent. Patented July 10, 1917.

Application filed June 7, 1915. Serial No. 32,541.

To all whom it may concern:

Be it known that I, CHARLES M. WEEKS, a citizen of the United States of America, residing at Springfield, in the county of 5 Hampden and State of Massachusetts, have invented a new and useful Punching-Bag Machine, of which the following is a specification.

My invention relates to improvements in 10 punching bags and mechanism for locking and releasing the same and for registering or indicating the force of the blows struck or received, and resides in certain peculiar mechanism whereby the punching bag is 15 held in inoperative position until released by a coin and elevated into operative position, and whereby said bag when struck causes to be registered the force of the blow and then resumes its inoperative position, 20 together with such auxiliary and subsidiary parts and members as may be needed in order to render the machine complete and serviceable in all respects, all as hereinafter set forth.

25 The primary object of my invention is to provide a punching bag machine which, although subject to coin control, enables the bag to be released and positioned normally, so that it can be struck as effectually and 30 naturally as a punching bag which is supported from below in the customary manner and left free and in operative position at all times.

A further object is to provide such a machine with means for indicating the force 35 of the blows which the punching bag receives.

Another object is to produce a machine 40 of this character wherewith the punching bag can be struck once only each time it is released, thus necessitating the insertion of a coin for every blow given said bag.

Still another object is to utilize the force 45 of the blow received by the bag, or the blow struck by the bag itself under the impulse or impetus imparted thereto by the blow received thereby, to withdraw said bag from operative position and relock the parts so that the bag cannot again be used until released with the aid of a coin.

With this machine there is no liability of injury to the fist of the person using the same and striking the bag, because the latter stands free and clear when the blow is de-

livered and then instantly passes away from 55 the fist which delivered the blow, so that the fist is not in contact with the bag at the time said bag delivers its blow.

My machine is simple in construction and 60 operation, effectual and satisfactory as an exerciser, and withal highly practicable and efficient.

Other objects and advantages will appear 65 in the course of the following description.

A preferred form or embodiment of the 70 invention, whereby I attain the objects and secure the advantages of the same, is illustrated in the accompanying drawings, and I will proceed to describe the invention with reference to said drawings, although it is to 75 be understood that the form, construction, arrangement, etc. of the parts in various aspects are not material and may be modified without departure from the spirit of the invention.

In the drawings, in which like numerals 80 designate like parts throughout the several views, Figure 1 is a side elevation of a machine that embodies my invention as aforesaid, one side of the box or housing being omitted and the top of the major portion of such housing being broken away in places; Fig. 2, a rear elevation of the upper portion of the indicator mechanism, the back side of that part of the housing that appears in this view being omitted; Fig. 3, a front elevation of the dial and pointer of the machine; Fig. 4, an enlarged detail showing parts of the indicator mechanism; Fig. 5, a transverse vertical section through 85 the housing, taken on lines 5—5, looking in the direction of the associated arrow, in Fig. 1; Fig. 6, an enlarged detail, in top plan, showing parts of the locking and releasing mechanism; Fig. 7, a view similar to 90 Fig. 5, except that the punching bag is shown in operative position in Fig. 7, while in Fig. 5 said bag is shown in inoperative position, the operating parts being disposed according to the positions of said bag in 95 the two views; Fig. 8, a view generally similar to Figs. 5 and 7, but illustrating an intermediate operation; Fig. 9, a detail showing parts of the registering and releasing mechanisms, and taken on lines 9—9, 100 looking in the direction of the associated arrow, Fig. 1; Fig. 10, an enlarged detail of the bag support; Fig. 11, an enlarged

detail of the bottom portion of the coin chute, and, Fig. 12, an enlarged detail of the plunger bar and associated parts.

In the first view, the coin box and chute are represented by dot-and-dash lines, in order to disclose to view operating parts or members that would otherwise be hidden, and the punching bag is shown in elevated position and the trap post in forward position by broken lines.

The housing of the machine consists of an oblong case 1 having at the rear end a vertical extension 2. In the top of the case 1, near the front end thereof, is a slot 3 for an 15 upstanding lever 4, and back of this slot and out of line with the same is a coin slot 6. There is a slot 7 in the top of the case 1, near the back end or under the chamber in the extension 2, for a bell-crank-lever 8. 20 The aforesaid top also has an intermediate opening 10 to which is fitted a trap-door or trap 11, such trap having its front edge hinged at 12 to said top, and opening downward. On the front of the extension 2, at 25 the top, is a dial 13 of any suitable character.

The lever 4 has its base pivoted at 14 to a bracket 15 that depends from the top of the case 1, and said lever extends through and 30 above the slot 3 to present the upper terminal of said lever above said top. A cord 16 connects the lever 4, at a point above the pivot 14, with the depending arm of the bell-crank-lever 8. The other arm of the 35 bell-crank-lever 8 is connected by a cord 17 with a detent 18, which latter forms a part of the indicator mechanism in the extension 2, presently to be described.

A coin chute 19 is located in the case 1 40 under the slot 6, and is hinged at 20 to the underside of the top of said case in such a manner that said chute may be swung transversely of said case. The chute 19 has a central longitudinal opening or slot 21 in 45 the outer side, and a central longitudinal slot 22 in the inner side at the lower terminal, such slots being respectively seen in full lines in Figs. 6 and 11. A money box 23 may be employed in the case 1, such box 50 having at the top a mouth-piece 24. The base of the chute 19 is received in the mouth-piece 24, and the latter must be large enough to permit said base to swing therein when said chute is operated.

55 A bracket 25 is secured to the front wall of the case 1 inside, also brackets 26 and 27, such brackets being arranged in the order named one above the other. A curved arm or cam lever 28 has its base pivoted at 29 to the inner terminal of the bracket 25 and extends upwardly therefrom. The bracket 26 extends inwardly and has an opening 30 therein to receive a thrust bar or plunger 31, such opening being in the same vertical plane with the coin-chute slots 21 and

22. The inner end of the bar 31 is pivoted at 32 to the lever 28, and at the outer end of said bar is a step or lug 33. The lever 28 is provided at the top with a stop pin 34 for which a stop 35 is provided on the 70 inside of the front wall of the case. A spring 36, having one end attached to the aforesaid front wall and the other end to the lever 28, tends to actuate said lever away from the chute 19 and normally retains said lever with its pin 34 in contact with the stop 35, and when said lever is thus disposed the step 33 at the outer end of the bar 31 lies across the passage through said chute, so that a coin dropped into said chute comes to 75 rest on said step. In the absence of a coin on the step 33, the bar 31, which is supported in and guided by the bracket 26, operates freely in and through the slots 21 and 22, whenever the lever 28 is actuated, but, if 80 a coin be present when said lever is rocked toward the chute 19, said coin is forced against the parts of the chute which form said slot 21 and so swings said chute on the hinge 20 toward the adjacent side of the 85 case, or in the same direction with said lever.

Pivotedly attached at 37 to the bracket 27 is a lock arm 38. The arm 38 extends inwardly and is provided adjacent to its 95 inner end with a fender 39 that rises from said arm. A hooked member 40 projects from the closed side of the chute 19 and loosely engages the arm 38, so that said chute and arm are connected and moved 100 together.

Behind the parts that are supported from the front wall of the case 1 is a pair of vertical rods or posts 41 set in a base plate 42, on the floor of said case, and a head plate 105 43, attached to the underside of the top of said case. Arranged to slide up and down on the posts 41 is a carrier for a punching bag 44, such carrier consisting of a pair of cross-heads 45 rigidly connected by an upright 46. The upright 46 is in the transverse center of the case, and has mounted at the upper end thereof a support or column 47 for the bag 44. There is an opening 48 in the top of the case, over the upright 46, 110 into which the column 47 extends and through which it operates. The upper cross-head 45 is provided with a forwardly-extending rod 49, into the path of which the outer and convex edge of the lever 28 extends, and said cross-head has at one end a lug 50, into the path of which the lock arm 38 normally extends. The arm 38 is held in place above the lug 30 by means of a spring 51, which has one end attached to the front 115 wall of the case and the other end to said arm, and the base of the chute 19 which is then in contact with the side of the mouth-piece 24 that is the more remote from the adjacent side of said case.

A hinge 52 is securely fastened to the top of the upright 46, and has the column 47 bolted thereto as shown at 53 in Fig. 10. The under leaf of the hinge 52 is mounted directly on the upright 46, and the upper leaf of said hinge receives the column 47. The hinge 52 is arranged with the pivotal connection at the rear, and the upper leaf of said hinge is made longer than the under leaf and projects forwardly beyond the latter, as shown at 54. Attached at one end to the part 54 is a chain 55, and this chain extends downwardly from the hinge to and through a pulley-block 56, which is fastened to the base plate 42, thence rearwardly to and through a pulley-block 57, which is attached to a spring 58, and finally forwardly to said plate, to which latter the other end of said chain is secured. The rear end of the spring 58 is attached to the back end of the case 1, and the pulley-block 57 is attached to the front end of said spring. The spring 58, acting through the chain 55, retains the hinge 52 closed and the column 47 in vertical position under ordinary conditions, and said spring exerts sufficient force to require a smart blow on the punching bag 44 to overthrow said column and open said hinge against such force. The spring 58 also causes the column 47 to assume an erect position again immediately after the blow has been struck which drives the bag rearwardly and downwardly, such blow being received on the front of said bag, and said column to descend into the case 1.

The column 47 should be resilient and therefore preferably consists of a spiral spring. The object of making the column 47 resilient is two-fold: First, the liveliness of the bag 44 is increased thereby, and, second, the shock incident to the action of the spring 58 in returning the column to erect position is absorbed to a great extent by the column spring, and the strain on the hinge 52 decreased.

The bag 44 is attached at the bottom to the top of the spring column 47 by means of a bolt, as shown at 59 in Fig. 10.

The trap 11 is so located in the top of the case 1 that it receives the bag 44 when the latter is overthrown or thrown down, and said trap opens downwardly on the hinges 12, under the force of the blow delivered to said bag and transmitted by the bag to said trap, to unlock or release the sliding carrier for the column 47 and the bag, and to operate the indicator mechanism, as will presently be explained. The trap 11 is provided on the underside near the back edge with a cross bar 60, and forward of said bar with a wedge block 61, the bottom of which block inclines upwardly and forwardly from the back-end. The cross bar 60 projects beyond the side edges of the trap 11 to engage the corresponding edges of the open-

ing 10 and limit the upward movement of said trap. The trap 11 is normally retained in its closed position by means of a post 62, which rests at the base on the floor of the case 1 and supports on the upper end said trap, the block 61 being in direct contact with the top of said post when the latter is erect. The base of the post 62 is hinged in front at 63 to the floor of the case, so as to enable said post to be tilted forward out of supporting relation to the trap 11. The top of the post 62 is beveled to correspond to the inclined surface of the block 61. A spring 64 extends between the back end of the case and the back side of the post 62 and is for the purpose of retaining said post in its upright supporting relation to the trap 11, and of returning said post to such relation. A chain 65 extends between the front side of the post 62 and the upper cross-head 45, and rocks said post on the hinge 63 forward and from beneath the block 61 when said cross-head is drawn up, as shown by dotted lines in Fig. 1, said post being actuated against the resiliency of the spring 64. When the aforesaid cross-head descends, the spring 64 rocks the post 62 back under the block 61, so that said post closes the trap 11, if open, and secures the same. The chain 65 is taut at all times.

A rock-shaft 66 extends longitudinally of the case 1 and has its ends journaled in bearings 67-67 at opposite ends of said case. A downwardly-extending rocker-arm 68 is secured to the rock-shaft 66 adjacent to one of the posts 41, and such arm has a hook 69 at the bottom to engage the adjacent end of the lower cross-head 45, when said cross-head is in elevated position, and retain the same with the connected members 105 in such position. A laterally-extending rocker-arm 70 is secured to the rock-shaft 66, and projects beneath a vertical plunger 71 which is under the center of the cross bar 60. The plunger 71 is supported by two lugs 72 which project, one above the other and beneath the bar 60, from a bracket 73 that is secured to the underside of the top of the case 1, back of the opening 10. A collar 74 is secured to the plunger 71, under the upper lug 72, to limit the upward movement of said plunger under the influence of a spring 75 which encircles said plunger between the under lug 72 and said collar. The rocker-arm 70 is normally held in contact with the bottom end of the plunger 71 by means of a spring 76 which latter extends between the bracket 73 and the free end of said rocker-arm. The spring 76 also serves normally to retain the hook 69 against the adjacent post 41 or in the path of the adjacent end of the lower cross-head 45, acting as it does through the rocker-arm 70, the rock-shaft 66 and the rocker-arm 68, so that when said cross-head is raised it actuates 125

said hook outwardly, said spring then yielding momentarily, passes above the same, and finally comes to rest thereon. The carrier for the column 47 and the bag 44 is thus retained in elevated position until the trap 11 is struck by said bag, when said trap drives down the plunger 71, against the resiliency of the spring 75, said plunger thrusts down the free end of the rocker-arm 70, against the resiliency of the spring 76, and said rocker-arm, acting through the medium of the rock-shaft 66, so actuates the rocker-arm 68 as to cause the hook 69 to be withdrawn from beneath the lower cross-head 45. The bag carrier is now free to descend. There must be sufficient space between the upper lug 72 and the trap 11 or the cross bar 60, when said trap is closed, to permit the latter to deliver the full force of its blow on the head of the plunger 71, more especially on account of the indicator mechanism which is operated by said plunger, and which will next be taken up.

Within the extension 2 is a bracket 77, and this bracket affords bearings for a shaft 78 that extends forward through the center of the dial 13 and has a pointer 79 secured thereon outside of said dial. The pointer 79 indicates or registers on the dial 13 the force of the blow struck the bag 44. A laterally-extending arm 80 is mounted loosely on the shaft 78 within the bracket 77, and this arm is provided on the back side with a pin 81. The pin 81 extends under a pin 82 that projects from the shaft 78 behind the arm 80 and parallel therewith, when the parts are normally disposed. A toothed wheel 83 is secured on the shaft 78 behind the pin 82, and the detent 18 engages with its free end said wheel. The detent 18 is pivoted at one end, as indicated at 84, to a bracket 85 that is fastened to the front wall of the extension 2, as is also the bracket 77. A spring 86, having one end attached to the front wall of the extension and the other end to the detent 18, retains said detent in engagement with the serrated wheel 83. Slidably mounted in two brackets 87 and 88 is a rod 89. The bracket 87 is fastened to the rear wall of the case 1 and the bracket 88 to the front wall of the extension 2, and these brackets position the rod 89 under the arm 80. The rod 89 has an enlargement or barrel 90 which normally rests on the bracket 87. A spring 91 is attached at the upper end to a cord 95, which is fastened to the shaft 78, and at the lower end to the front wall of the extension, and tends to rotate said shaft in the direction of the arrow in Fig. 2. The spring 91, therefore, actuates or holds the wheel 83 in locking engagement with the detent 18, on the one hand, and, when said detent is withdrawn from said wheel, said spring forces the pin 82 against the pin 81

and the arm 80 onto the top of the rod 89, on the other hand. A horizontal operating lever 92 is pivotally connected at 93 with a pair of lugs 94 at the bottom of the brackets 73, and extends forwardly to and through a slot in the plunger 71 and rearwardly to and through a slot in the barrel 90, as clearly shown in Fig. 1. That portion of the lever 92 that is forward of the pivot 93 is much shorter than that portion that is behind said pivot, wherefore a comparatively slight movement imparted to the front end of said lever is greatly increased at the rear end. 75

The plunger 71 is driven downwardly 80 with considerable force, by the trap 11 when struck by the bag 44, as previously explained, and said plunger in its descent forcibly rocks the lever 92 on the pivot 93, carrying the front end of said lever down and the rear end up. The rear end of the lever 92, thus suddenly and forcibly elevated, actuates the rod 89 upwardly and thrusts said rod with great force against the arm 80, while in turn imparts, through 90 the medium of the pins 81 and 82, a rotary motion to the shaft 78 in the direction contrary to that indicated by the arrow in Fig. 2, with the result that the pointer 79 is carried around to the right. The shaft 95 78 in rotating winds up the cord 95 and stretches the spring 91 until the force of the latter overcomes the impetus imparted to said shaft by the mechanism which caused it to rotate. The wheel 83 is carried around 100 with the shaft 78, its teeth clicking past the detent 18, until the parts stop, when said detent holds said wheel and prevents said shaft from being reversed by the force of the spring 91. The pointer 79, which rotates with the shaft 78, is thus left with its point adjacent to the number on the dial 13 which indicates the force of the blow received by the punching bag. 105

The arrangement of parts is such that 110 the pointer 79 points to the number at the top of the dial 13 normally and before the blow is struck, and to restore said pointer to this initial position the lever 4 is rocked forward. The lever 4 when rocked forward 115 draws the cord 16 forward with it and thus actuates the bell-crank-lever 8 to draw down the cord 17 and actuate the detent 18, against the resiliency of the spring 86, out of engagement with the wheel 83. This operation releases the shaft 78 to the action of the spring 91, and said spring rotates the shaft 78 in the reverse direction until the pin 82 comes to rest on the pin 81, it being understood that the arm 80 which 125 carries said pin 81 is already at rest on top of the rod 89, and that said rod has been permitted to descend into its low position. It should here be observed that the upward thrust of the rod 89 does not throw the arm 130

80 so far that said arm does not immediately settle down again onto said rod, it being the parts actuated by said arm and its pin 81 that receive the greatest impetus, due 5 to the fact that the point of contact between the pins is so much nearer the axis of the shaft than the point of contact between said rod and arm, and the speed imparted through said pins is consequently so very 10 much greater than that received and imparted through the more distant members, even in spite of the spring 91. The spring 91 is comparatively light. The inertness on the part of the shaft 78 and the members 15 thereto is a factor also in limiting the upward movement of the arm 80. The lever 4 is released, as soon as the pointer 79 arrives at initial position, and the spring 86 rocks the detent 18 into contact with the 20 wheel 83 once more, in readiness to hold said wheel the next time it is impelled forward, said lever and the connections between it and said detent readily returning to their former positions or conditions with the 25 tent.

The operation of the machine as a whole is described as follows, it being assumed that the movable parts and members are all initially disposed, and that a coin 96, 30 Figs. 8 and 12, has been dropped through the slot 6 into the chute 19 and been received on the step 33 of the thrust bar 31. The punching bag 44, which is down on top of the case 1, is first grasped and raised 35 from said top, the column 47 coming up through the opening 48. The carrier for the column 47 is elevated with said column, the cross-heads 45 of said carrier sliding on the posts 41, and the upper end of the chain 55 40 is taken along with the hinge 52, thus increasing the tension of the spring 58. The force of the spring 58 is sufficient to balance the weight of the carrier, so that the hinge 52 is not opened when the bag 44 is raised. 45 The pin 49 on the upper cross-head 45 of the rising carrier actuates the lever 28 against the resiliency of the spring 36, toward the chute 19, and said chute is swung toward the adjacent side of the case in time 50 to swing the arm 38, against the resiliency of its spring 51, out of the way of the cross-head lug 50. If there were no coin between the outer end of the bar 31 and the adjacent edges of the slot 22, said bar would 55 simply pass through said slot without disturbing the chute 19 or removing the arm 38 from locking position, and in that event the upward movement of the bag would be checked as soon as the lug 50 encountered 60 said arm, which is precisely what occurs when an attempt is made to raise said bag without inserting the coin. The bag cannot be raised into striking position or high enough for any practical purpose without 65 the coin, the limit of upward movement in

that case being determined by the distance between the lug 50 and the arm 38 as they are disposed in Fig. 5.

By the time the pin 49 reaches the major swell of the lever 28, the arm 38 has been 70 moved out of the way of the lug 50 and said lug is on a level with said arm and in a position to ride past said arm and receive the fender 39 against the adjacent side of said lug—see Fig. 8. The fender 39 now 75 bears against the lug 50 and prevents the arm 38 from being swung by the spring 51 into the path of said lug, and so interfering with the descent of the carrier. After the pin 49 passes above the major swell of the 80 lever 28, the spring 36 returns said lever to place in contact with the stop 35, and in so doing causes the bar 31 to be withdrawn from the coin 96, when the latter drops down through the bottom of the chute 19 85 and the mouth-piece 24 into the box 23.

During the raising of the bag 44 the chain 65 draws the post 62 from beneath the block 61, the trap 11 thus being left supported at the rear end solely by the plunger 71. 90

When the bag 44 is raised to the full height, as best illustrated in Fig. 7, the rocker-arm hook 69 enters beneath the lower cross-head 45 and the rocker-arm 68 retains 95 the carrier with the column 47 in elevated position and said bag in striking position. The bag is now released by the operator and he prepares to strike the same.

The operations which are dependent on 100 the raising of the punching bag, which is done by hand, occur quickly, especially if the bag be raised quickly, and the other operations take place almost instantaneously, as will readily be understood. 105

Having raised the punching bag into striking position, the operator next proceeds to deliver his blow. Under the blow which the bag 44 receives from the fist of the operator, said bag falls or is driven with 110 great force downwardly and rearwardly onto the trap 11, the spring 58 yielding and the hinge 52 opening under the force of the impact of such blow. The spring 58 yields for an instant only and then it contracts 115 suddenly, closes the hinge 52 with a snap, thus causing the column 47 to become erect, and draws down the carrier until the bag 44 is on the top of the case 1 and entirely out of operative position, all with the aid 120 of the chain 55 and the pulley blocks 56 and 57. The impact of the blow struck the trap 11 by the bag brings about the release of the lower cross-head 45 from the rocker-arm 68, so that the parts can descend, said 125 trap acting through the plunger 77, the rocker-arm 70 and the rock-shaft 66, and the aforesaid impact also causes the pointer to spin around and register on the dial 13 the force of the blow struck the bag, the man- 130

ner in which such registration is accomplished having been fully explained hereinbefore. During the descent of the carrier with the bag, the pin 49 actuates the lever 28, but idly this time, the lug 50 rides down the fender 39 and past the arm 38, which latter swings into locking position over said lug as soon as the lug passes below the horizontal plane of the arm, the chute 19 swings back into its former position, and the post 62 is permitted to rock back into place beneath the block 61, closing the trap 11 while so doing, unless the united action of the springs 75 and 76 has already brought about that operation.

It is clear from the foregoing that the punching bag, through the medium of the operating mechanism therefor, is both self-retracting and self-locking, and it might also be said that said bag is self-registering, or at least that the bag automatically registers the force of the blow which it receives. The only manual operations, aside from the punch, are those required to insert the coin, raise the bag, and reset the pointer. This last act can be attended to, by rocking the lever 4 forwardly and then releasing it, as soon as the last record has been taken or noted, and in any event should be attended to before the bag is struck again.

What I claim as my invention, and desire to secure by Letters Patent, is—

1. In a punching-bag machine, a rising and falling carrier, a support yieldingly mounted on said carrier, a punching bag mounted on said support, and operating means for said carrier.

2. In a punching-bag machine, a movable carrier, a resilient support mounted on and pivotally connected with said carrier, means to retain said support normally in an upright position and to restore it to such position, a punching bag attached to said support, and means to move said carrier to locate said bag in and out of operative position.

3. In a punching-bag machine, a carrier, a resilient support yieldingly mounted on said carrier, yielding means arranged and adapted to retain said support in an upright position, under normal conditions, and to raise said support, when overthrown, into such position, and a punching bag attached to said support.

4. In a punching-bag machine, a carrier, a hinge attached to said carrier, a resilient support attached to said hinge, yielding means attached to said hinge and capable of retaining said hinge in closed position with said support erect, under normal conditions, and of closing said hinge when opened and raising said support into vertical position, and a punching bag attached to said support.

5. In a punching-bag machine, a down-

wardly spring-pressed rising and falling carrier, a support yieldingly mounted on said carrier, a punching bag mounted on said support, and locking and releasing means for said carrier.

6. In a punching-bag machine, a carrier, a support, pivotal means to connect said support with said carrier, yielding means arranged and adapted to act on said pivotal means to erect said support, when overthrown, and normally to retain said support erect, and a punching bag mounted on said support.

7. In a punching-bag machine, a rising and falling carrier, locking and releasing means for said carrier, a support, pivotal means to connect said support with said carrier, yielding means arranged and adapted to erect said support, when overthrown, and normally retain it in vertical position, and to lower said carrier, when the latter is released, and a punching bag attached to said support.

8. In a punching-bag machine, a carrier, a hinge attached by the under leaf to said carrier, a support attached to the upper leaf of said hinge, a spring connected with said upper leaf and adapted normally to retain said leaf closed with said support erect, and a punching bag mounted on said support.

9. A punching-bag machine comprising a case having an opening therein, a normally-depressed rising and falling carrier in said case, a support yieldingly mounted on said carrier and adapted to be drawn up in said opening, and a punching bag mounted on said support, the arrangement of parts being such that said support can be overthrown only when said carrier is in its elevated position.

10. In a punching-bag machine, a normally-depressed rising and falling carrier, a support yieldingly mounted on said carrier, a punching bag mounted on said support, said members being adapted to be raised to locate said bag in striking position, means to lock said members in such position, and means operated by said bag when thrown down to withdraw said first mentioned means from locking position.

11. The combination, in a punching-bag machine, with a case having an opening therein and provided with a trap, a normally-depressed rising and falling carrier in said case, a normally erect support yieldingly mounted on said carrier and adapted to be drawn up in said opening, and a punching bag mounted on said support, said trap being within range of said bag when thrown down from striking position, of means to lock said carrier when elevated, and means operated by said trap, when the latter is struck by said bag, to disengage said locking means from said carrier.

12. The combination, in a punching-bag

machine, with a case having an opening therein and provided with a trap, a movable support for said trap, a normally-depressed rising and falling carrier in said case, a normally erect support yieldingly mounted on said carrier and adapted to be drawn up in said opening, and a punching bag mounted on said last-mentioned support, of a connection between said carrier and said first-mentioned support, whereby the latter is moved to release said trap when said carrier is elevated, rocking members arranged to lock said carrier in elevated position, and a plunger between said trap and one of said rocking members, the arrangement of parts being such that said bag when thrown down strikes said trap and causes the same to actuate said plunger and thereby to release said carrier.

13. The combination, in a punching-bag machine, with a case having an opening therein and provided with a trap, of a normally-depressed rising and falling carrier in said case, a normally erect support yieldingly mounted on said carrier and adapted to be drawn up in said opening, a punching bag mounted on said support, said bag, when raised and in striking position, being within striking distance of said trap, a tilting post arranged in said case beneath said trap, and spring-pressed into supporting relation therewith, a connection between said carrier and said post, whereby the latter is withdrawn from such relation when said carrier is raised, and unlocking mech-

anism for said carrier, such mechanism being actuated by said trap when struck by said bag.

14. In a punching-bag machine, a case, a punching bag, and means in said case to support said bag from beneath movably mounted in said case in order to position said bag in striking position and out of such position.

15. In a punching-bag machine, a case, a punching bag, means in said case to support said bag from beneath movably mounted in said case in order to position said bag in striking position and out of such position, mechanism for locking said supporting means when the supporting means is disposed to locate said bag in said striking position, and means adapted to release said locking mechanism when the bag is thrown down from said striking position.

16. In a punching-bag machine, a case, a punching bag, downwardly spring-pressed means in said case to support said bag and locate it in striking position and out of such position, and locking mechanism for said supporting means when elevated against the force of its spring, said mechanism being operated by said bag, when the latter is thrown down from striking position, to release said supporting means to said spring.
